DESIGN FOR A PLATE OR SIMILAR ARTICLE

Yukio Buma, New York, N. Y., assignor to
Morimura Bros. Inc., New York, N. Y., a cor-
poration of Japan

Application October 16, 1935, Serial No. 59,075

Term of patent 7 years

To all whom it may concern:

Be it known that I, Yukio Buma, a subject of
the Emperor of Japan and a resident of the city,
county, and State of New York, have invented
a new, original, and ornamental Design for a
Plate or Similar Article, of which the following
is a specification, reference being had to the ac-
companying drawing, forming part thereof.

The drawing is a plan view of a plate showing

my new design, a repeat unit of which is contained
between the dotted lines. Said unit is repeated
about the circumference of the plate in the rela-
tion indicated by the extension of the detailed
showing beyond the dotted lines.

I claim:

The ornamental design for a plate or similar
article, as shown and described.

YUKIO BUMA.
